UNITED STATES PATENT OFFICE

2,008,852

APPARATUS FOR THE TRANSFORMATION
OF THE SUGAR CANE INTO SAW-DUST

Fernando Moreu Diaz, Motril, Spain

Original application September 21, 1931, Serial
No. 564,184. Divided and this application Feb-
ruary 20, 1933, Serial No. 657,733. In Spain
January 7, 1931

1 Claim. (Cl. 146—123)

My invention relates to an apparatus here-
after specified for shredding the sugar cane to
a kind of saw-dust.

It is based on the mechanical concept of re-
ducing the exterior pressure on the cane to the
shredding forces of rotating toothed circular
saws, operating at a high angular speed of about
2000 to 3000 revolutions per minute, thereby sup-
plying the kinetic energy $\frac{1}{2} m v^2$ required for the
10 complete disintegration of the sugar cane.

It will be clearly understood that according to
the above mentioned formula, by increasing the
speed v , the mass m brought into action is re-
duced to a minimum.

15 I succeeded in suppressing the encumbrance
of great mass of the mills or rollers or other
hydraulic apparatus including all the disad-
vantages thereof, as, for instance, considerably
less space and power required, and consequent
20 reduction of high labor costs, maintenance and
initial costs of the installation.

The present invention is based on the mechanical
principle of eliminating all exterior hydraulic
25 pressure, replacing the same by shredding
forces of the rotating circular saws and not only
comprises the advantages already mentioned
above, but also other of mechanical nature of still
greater importance specified as follows:

In the present practice the great hydraulic
30 pressures of the mills or other mechanical appa-
ratus causes many impurities in the juice as parts
of the cellular materials and other elements of
the young stalk as pepsine, albuminoides, gums,
silex, coloring substances and wax, making it
35 necessary to purify the said juice again.

The invention prevents the pollution of the
juice as the cellular sacks are subjected to only
small cutting forces. Furthermore, in the cellular
40 processes still in use, the reduction con-
tents in sugar of the woody portion of the cane
(bagasse) is accomplished by the addition of
large quantities of water, which means higher
manufacturing costs for the evaporation of the
water placed in circulation.

45 The present invention effects the separation
of the pure juice without any addition of water,
unless a reduction to zero of this content of
sugar is desired.

This application is a division from the copend-
50 ing application Serial No. 564,184, filed Septem-

ber 21, 1931.

A preferred form of this apparatus is illustrated
in the drawing.

With reference to Figs. 1 and 2 of the accom-
panying drawing, showing respectively a longi-
tudinal and a transverse section, the apparatus
is composed of an electric motor coupled to a
pulley or pinion 4, driving the shaft 12 mounted
on roller bearing 1. On said shaft 12, by means
of a special construction 14 and 3 are mounted
10 the necessary circular saws 2, the number and
diameter of which depend upon the imposed
production of the engine.

On the other end of the shaft 12 a fly wheel 10
is mounted. By means of a gear construction 15
5 and 6 two toothed shaft drivers 7 are provided
for supplying the sugar cane through the hopper
13 to the circular and slantingly mounted saws.
The shafts 7A are mounted in two bronze bear-
ings 8 in the frame 9. This frame 9 is closed by 20
two steel plates 11.

Numerals 15 and 16 denote shielding members
over the saws leaving only a narrow space be-
tween the saw teeth and said members.

The invention having been set forth, what is 25
claimed as new and useful is:

An apparatus in which are provided means of
complete disintegration of the vascular fibrous
material of the cane in such a manner, that the
small cellular sacks of the cane are ruptured 30
without experiencing any hydraulic exterior pres-
sure only by means of the shredding forces of the
circular saws, said apparatus comprising a motor
driven horizontal shaft, circular saws mounted
on said shaft at a predetermined inclination with
respect to the axis of said shaft, and shielding
members substantially inclosing the upper por-
tion of the saws mounted to leave a very narrow
space between said members and the saw teeth,
said shielding members providing a feed open-
ing between their edges, a housing forming to-
gether with said shielding members a substan-
tially complete enclosure for said circular saws
and consisting of end standards provided with
bearings for said shaft and aprons forming down-
ward continuations of said shielding members,
filling completely the front and rear spaces be-
tween said end standards.
